2 SHEETS—SHEET 2.

UNITED STATES PATENT OFFICE.

ALEXANDER W. BUCHANAN, OF COLORADO SPRINGS, COLORADO.

FLOOR-CLEANER.

Specification of Letters Patent.

Patented Mar. 2, 1915.

1,130,064.

Application filed July 8, 1913. Serial No. 777,809.

To all whom it may concern:

Be it known that I, ALEXANDER W. BUCHANAN, a citizen of the United States, residing at Colorado Springs, in the county 5 of El Paso and State of Colorado, have invented certain new and useful Improvements in Floor-Cleaners, of which the following is a specification.

My invention relates particularly to a 10 floor cleaning device in which a strip of suitable cloth is the cleaning medium employed and in which it is desirable, from time to time, to bring a new and clean portion of said cloth into contact with the floor, 15 displacing that portion which has been in contact and has gathered as much dirt as it will hold.

The subject matter of this application is a 20 device which provides for readily effecting such change with but slight effort on the part of the operator and without lifting the implement from the floor.

A further feature of this device is that the contact part or element and the part or 25 element provided to take up the soiled part of the cleaning cloth are one and the same, and that the cleaning cloth itself, rolled upon the contact part, forms the cushion for applying to the floor that part of the cleaning cloth which is in action.

I have heretofore referred to my invention as a floor cleaner but it will be readily apparent that it may be used, with or without modifications, for other similar walls, 35 poses, as, for example, for cleaning walls, large windows, etc., or for the treatment of any substantially plane surface. And though I show and describe hereinafter several modifications of the invention, includ- 40 ing that form which I consider to be preferable to all others, such detailed disclosure is for the purpose of exemplification only, as the invention may be embodied in a great variety of other forms. But the scope of the 45 invention is defined in the following claims in which I have endeavored to distinguish it from the prior art so far as known to me without, however, relinquishing or abandoning any portion thereof.

50 Referring now to the accompanying drawings Figure 1 is a front elevation of the preferred form of my invention; Fig. 2 a side elevation thereof; Fig. 3 an enlarged detail partly in section of the end of the

cleaner roll; Fig. 4 a transverse section 55 showing the preferred means for attaching the end of the cloth to the roll; Fig. 5 a side elevation of a modified form; Fig. 6 a side elevation of a further modification, and Fig. 7 a detail of a tool employed in connection 60 with the device.

The same character of reference is em- 65 ployed in connection with each part wher- ever it occurs throughout the several views.

Referring first to the preferred form 65 shown in Figs. 1, to 4 inclusive, the frame of the implement comprises a U-shaped metal support 8 having the parallel sides 9, 9 in which the rotary members of the device are journaled and which frame is connected 70 by a socket 10 with a handle 11 of any suit- able character but preferably like the handle of the carpet sweeper in common use. If desired for greater rigidity, the support 8 may be braced by suitable cross-bars but if 75 it be made of sufficient weight of metal this will not be necessary. Between the ends of the side members 9, 9 is journaled the con- tact or friction roll 12 which is provided at 80 its ends with trunnions 13, 14 journaled in suitable openings in the ends of the frame. The latter being fairly resilient by reason of its construction and material, the roll 12 may be inserted or removed by merely forc- 85 ing the ends of the frame sufficiently apart for the purpose. Upon one end of the con- tact roll and concentric therewith is secured a disk 15 preferably of sheet metal which is formed with a number of rectangular 90 openings 16 stamped therein with which openings a pawl 17 formed as a prolonga- 95 tion of the side frame member 9 co-operates. (See Figs. 2 and 3).

At a suitable distance above the contact roll the side members of the frame are notched as at 18, the bottoms of the notches being rounded to afford bearings for the trunnions 19 of a magazine or supply reel 20 upon which the strip of cloth to be used in the cleaner is wound before the latter is ready for use. The ends of the reel 20 are formed or provided with disks 21 somewhat larger in diameter than the roll of cloth when the magazine is full, one or both of which disks are notched on their peripheries 100 as at 22 at suitable intervals for the recep- 105 tion of bosses 23 upon the stop bar 24. The latter is mounted upon a spring or springs

25, attached to the frame as at 26, which serve to normally hold the stop bar with its bosses bearing upon the disks 21 and when the notches in the latter are in register with 5 the bosses on the stop bar the magazine roll is held from turning. Upon the handle 11 in a position convenient for the operator is located a bell-crank 27 which is pivoted in a kerf or groove therein and connected by a 10 wire or cord 28 with the stop bar 24, which wire may be guided at suitable intervals by screw-eyes 29, 30.

With the device thus described any suitable means may be used for securing the 15 ends of the strip of cleaning fabric to the rolls, but I prefer the very simple device shown in Fig. 4 which consists in tacking a short friction strip 31 of rather rough fabric longitudinally of the roll body and inserting 20 the end of the cleaner strip to be wound between the friction strip 31 and the roll, when the strip of fabric may be wound up on the roll, the succeeding layers holding the strip 31 in close contact with the end of 25 the cleaning strip, and thereby preventing the latter from slipping.

As heretofore stated the contact roll is mounted in its bearings by simply spreading the branches of the frame sufficiently 30 to permit the roll trunnions to be inserted in the bearing openings thereof. The magazine or supply reel after a suitable amount of material has been wound thereon is dropped into its bearing notches on the frame, the stop bar 24 being drawn or 35 pressed backward to permit this to be done, and when released keeping said reel in position. The end of the cleaning strip is then passed through the frame between the reel 40 and roll and attached to the contact roll in the manner above described and sufficient of the material wound on the latter to form the necessary cushion, the stop bar in the meantime being withdrawn sufficiently to 45 permit the magazine reel to revolve and feed the fabric. The implement is then ready for use and the contact roll is rubbed forward and backward over the floor to be cleaned, being prevented from turning 50 in one direction by the pawl 17 and perforated disk 15 and in the other by the tension of the strip of cleaning fabric 32 which is restrained by the magazine reel and the stop bar coacting therewith. When 55 it is desired to use a new section of the cleaning fabric the stop bar is withdrawn from contact with the disks 21 so that the magazine reel is free to turn and thereupon the contact roll is rubbed along the floor with sufficient pressure to cause it to revolve 60 in the direction permitted by its pawl and ratchet and thereby to wind a section of cloth from the magazine reel. The stop bar is then released and again locks the 65 magazine reel. The used portion of the

strip is of course wound within the newly supplied portion and the dirt, dust and adherent matter accumulated thereon is therefore wound up within the roll. Thus fresh surfaces or portions of fabric are supplied 70 from time to time without the operator lifting the implement from the floor and when the strip upon the magazine reel is exhausted the reel and roll are taken out of the device, the strip removed from the contact 75 roll upon which it has been wound and a new strip wound upon the magazine reel. Or of course if desired the old strip may be cleaned in some suitable manner and returned to the magazine reel. Obviously 80 the strip may be treated with material to cause the particles of dust, etc., to adhere to it or with any liquid or other substance which it is desired to apply to the floor or surface to be treated.

The other forms of the invention illustrated in the drawings differ from that just described only in certain details. In that shown in Fig. 5 a different means is employed for controlling the reel in which an ordinary ratchet 15' is substituted for the perforated disk 15 and a spring pawl 17' of any suitable or usual design is secured to a rivet 33 upon the frame and coacts with the ratchet in the usual manner. Instead of the notched disks and stop bar for the magazine reel of the previously described modification I employ in this modification a friction brake 34 having a pad of cloth or other friction material 35 upon the under face thereof and fastened by a spring or springs 36 to the frame at 37. The same means may be employed for retracting this brake bar as described in connection with the stop bar 24 but I have 100 shown the bell-crank lever 27' as slightly changed from that of the first described form of the invention, it being formed with lugs 38 which span the handle 11' and are pivoted on the outside thereof. The operation of this device is substantially like the former, it being only necessary, in order to change the portion of the cleaning fabric, used to retract the brake bar 34 so that the magazine reel may revolve, and then cause 110 the contact roll to revolve in the direction permitted by its ratchet and pawl by pressing it into contact with the floor or surface being cleaned and moving it along the same.

In the modification shown in Fig. 6 the contact roll is identical with that shown in Figs. 1 to 3 inclusive. The magazine reel 20', however, is in the form of parallelepipedon shown as square in cross section, with which co-operates a spring 39 having a flattened portion to co-operate with the sides of the reel to prevent rotation thereof and an angular portion which is adapted to fit over the corners of the reel for the purpose of preventing its rotation, thus providing for 125 130

holding the reel after each eighth of a rotation. The means for pulling upon the bell-cord or wire may be either of the bell-cranks heretofore described or any other suitable device. In this modification I have shown features which are also applicable to either of the other two modifications, if desired, one of which consists in a somewhat enlarged trunnion 19' on the magazine reel provided with a square recess 42 with which a crank 43, shown in Fig. 4, may be used to turn the reel to wind up the fabric when desired. The other feature referred to is a protecting or buffer strip 51 of rubber or other suitable material for preventing marring of any furniture with which the implement may come into contact.

It will be seen that each of these forms of my invention is provided with a contact roll upon which the cleaning fabric may be wound from time to time as it becomes soiled or inefficient, the dirt and other matter accumulated on the fabric being inclosed by the following layer of material so that it is firmly held during the subsequent operation of the implement and cannot be blown away or otherwise disseminated in the room or compartment being cleaned.

Obviously, if it is desired to secure firmer contact between the implement and the surface being treated, either or both the reel and roll or the frame may be made of heavy material but preferably the weighty material is put into the roll because the latter may be readily exchanged for a lighter roll when occasion demands.

I claim:

1. In a device of the class described, a frame, a contact roll mounted in the end thereof, means for attaching a strip of fabric to be wound thereon to the roll, means engaging the roll for preventing rotation of the contact roll in one direction but permitting its rotation in the other direction, and means for engaging the strip to normally prevent its being wound upon said roll.

2. In a device of the class described, a frame, a roll mounted in the end thereof provided with means for securing the end of a strip of fabric thereto, a ratchet on the roll and a pawl on the frame adapted to permit the roll to turn in a direction to wind the strip of fabric thereon but to prevent its rotating in the opposite direction, a reel mounted on the frame and adapted to have the other end of the fabric strip wound thereon and means under the control of the operator for normally preventing rotation of the reel.

3. In a device of the class described, a frame, a contact roll mounted in the end thereof and adapted to receive material to be brought in contact with a surface to be cleaned and to have the same wound thereon, a ratchet secured to one end of said

roller, a pawl secured to the frame and cooperating with said ratchet to prevent its rotation in one direction, a magazine reel also mounted on the frame, and means for normally preventing rotation of the magazine reel.

4. In a device of the class described, a frame, a contact roll mounted in the end thereof in position to engage a surface to be cleaned, means for preventing the rotation of said roller in one direction while permitting its rotation in the other direction, a magazine reel also mounted in the frame, and a releasable catch under the control of the operator for normally preventing the rotation of the magazine reel.

5. In a device of the class described, a frame, a contact roll mounted in the end thereof in position to engage a surface to be cleaned, means for preventing the rotation of said roller in one direction while permitting its rotation in the other direction, a magazine reel also mounted in the frame, spring actuated means for preventing the rotation of the magazine reel, and means for withdrawing the same from contact with the reel.

6. In a device of the class described, a frame, a contact roll and a magazine reel mounted in the frame, a strip of fabric connected at its opposite ends to the reel and roll respectively and partially wound thereon, pawl and ratchet means for preventing the turning of the contact roll to unwind the strip but permitting said roll to turn in a direction to wind the strip, means normally preventing the rotation of the magazine reel under the pull of the strip of fabric and means for releasing the last said means to permit the magazine reel to turn and pay off the fabric.

7. In a device of the class described, a frame, a contact roll and a magazine reel mounted in the frame, a strip of fabric connected at its opposite ends to the reel and roll respectively and partially wound thereon, pawl and ratchet means for preventing the turning of the contact roll to unwind the strip but permitting said roll to turn in a direction to wind the strip, means for normally resisting the rotation of the magazine reel under the pull of the fabric comprising notched disks on the ends of said reel, a stop bar having projections adapted to enter the notches, a spring carrying the stop bar, a handle, a lever on the handle, and connections from the lever to the stop whereby the latter is retracted from contact with said disks.

8. In a device of the class described, a frame having the side members 9, one of said members being resilient and having formed integral therewith a pawl 17, a roll journaled between said side members, a disk on an end of said roll having a circular

series of apertures with which said pawl is adapted to engage and means for holding the end of a strip wound on said roll.

9. In a device of the class described, a handle, a frame attached to said handle, a magazine reel mounted in said frame, a supply of cleaning fabric in the form of a strip having one of its ends removably attached to said magazine reel and being wound upon said reel; a contact roll revolvably mounted between the ends of said frame and having the other end of said cleaning fabric removably attached to it; said contact roll being adapted to press said cleaning fabric into contact with the surface to be cleaned and to be revolved in its bearings by frictional contact with the surface to be cleaned; means for normally preventing rotation of said

contact roll in either direction, consisting of a pawl and ratchet acting in one direction and a tension of the strip of cleaning fabric acting in the other direction; means for maintaining the tension of the cleaning fabric by locking the magazine reel upon which said fabric is wound; means under control of the operator for releasing the tension on the cleaning fabric by unlocking the magazine reel and thus leaving the contact roll free to be revolved in one direction by frictional contact with the surface to be cleaned, thereby winding upon itself a portion of said cleaning fabric.
